UNITED STATES PATENT OFFICE.

FRANK STONE, OF WORCESTER, MASSACHUSETTS, ASSIGNOR TO MUNROE ORGAN REED COMPANY, OF SAME PLACE.

SUB-BASS ATTACHMENT FOR REED-ORGANS.

SPECIFICATION forming part of Letters Patent No. 340,636, dated April 27, 1886.

Application filed June 1, 1885. Serial No. 167,210. (No model.)

To all whom it may concern:

Be it known that I, FRANK STONE, a citizen of the United States, residing at Worcester, in the county of Worcester and State of Massachusetts, have invented certain new and useful Improvements in Sub-Bass Mechanism for Reed-Organ; and I declare the following to be a description of my said invention sufficiently full, clear, and exact to enable others skilled in the art to which it appertains to make and use the same, reference being had to the accompanying drawings, which form a part of this specification.

The object of my present invention is to provide a pneumatic sub-bass for reed-organs, which can be manufactured as a separate article of merchandise and furnished to organ-manufacturers to be applied in simple and ready manner by them, as desired, in the construction of any style of reed-organ in which an exhaust-bellows is employed; also, to provide a sub-bass action that can be connected with and controlled by the manual-keys without materially interfering with the delicacy of touch at that part of the manual where the sub-bass connections are located; also, to provide a sub-bass of superior quality and power, and which will respond in a prompt, efficient, and full-toned manner; also, to provide for the reduction of the spacings or scale from that of the sub-bass to conform to the scale of the regular action, and allow connections to be made direct with the manual or action, as hereinafter explained. These objects I attain by a pneumatic sub-bass mechanism, constructed and organized for operation as illustrated and set forth, the particular subject-matter claimed being hereinafter definitely specified.

In the drawings, Figure 1 is a plan view of my improved pneumatic sub-bass, a part being shown in section, and the pointers of the manual-keys in relation to the valve-levers being indicated. Fig. 2 is a view showing part front part vertical section at line *ww*; and Fig. 3 is a vertical transverse section at line *xx*, showing the pneumatic sub-bass and its relative relation to the manual and organ action.

In reference to parts, A denotes the action-board of a reed-organ or top of the air-chamber A', from which the air is exhausted by suitable means, or in ordinary manner.

B denotes the box or case inclosing a chamber, B', that contains the sub-bass mechanism, which casing is adapted to stand upon the top 55 of the action-board A, one or more air-passages, *a*, being formed through said board, so that the chambers B' and A' are connected and the air-pressure equalized therein.

C indicates the tube-board, containing the 60 sub-bass reeds R, which are inserted in cells, disposed as shown. The tube-board is supported within the chamber B', so as to allow space at both front and rear thereof and beneath its lower edge, the mouths of the reed-cells opening through the top of the board, and a suitable mute, M, is arranged in connection therewith for stopping off the action of the sub-bass when desired.

In the rear part of the chamber B' are arranged the series of valves D, that close the 70 passages *e* from the reed-cells into said chamber, and in the front part thereof are arranged a corresponding series of pneumatic motors, F, constructed and disposed in the manner indicated, for opening or expanding toward the valve D, while a series of reciprocating tracker pins or rods, I, are arranged along the lower edge of the tube-board, which fit between the ends of the pneumatic motor-fingers F and the 80 lower ends of the valves D, as indicated. The length of said pins I is made equal to the distance between the valve and its corresponding pneumatic, so that the opening or expansion of the pneumatic will force open the valve. 85 The pneumatic is made of thin pieces of wood with sides of soft flexible leather or similar material. A small hole is formed through the back to allow air to leak through sufficient for closing the pneumatic motor when the external air-pressure is stopped off by the pressure 90 exerted from the spring *d* of the valve D transmitted to the pneumatic by the rod I.

At the front of the case B is a tracker-board, H, having a series of openings, J, spaced to 95 correspond with the spacings or scale of the manual-keys K, and from these openings passages extend downward in variously-inclined order, (see dotted lines in Fig. 2,) so that their lower ends, which lead into the respective 100 pneumatics, correspond in position to the spacings or scale of the sub-bass reeds.

On the exterior surface of the board H, in connection with the openings J, is a series of

valves under control of the manual action for admitting the external air into the pneumatics, so that they will expand in the exhausted chamber B' and open the sub-bass valves accordingly as the keys are depressed.

In the present instance the connection of the sub-bass and manual action is effected by a series of levers, L, corresponding in number with the pneumatics and valves, which are furnished at their rear ends with stop pads or valves L', for closing the respective openings J. The levers are fulcrumed on a suitable support-bar, N, with their forward ends in position to respectively engage with buttons P', fixed on the pitman-pins P of the regular organ-action, and by means of which the motion of the manual-keys is transmitted to the inlet-stops L' as the said keys are depressed for opening the valves D of the regular organ. The forward end of the levers L may be separated horizontally, as at m, and a set-screw, s, fitted in the lower part to press against the upper portion for effecting adjustment thereof in relation to the button P', for regulating the throw of said levers, and cause the inlet stops or valves L' to open at the proper instant of time. If preferred, the air-inlet openings J might be at the front of the board H, and the opening and closing of said passages might be effected by other simple devices (in lieu of the levers L) arranged in a manner to be controlled by the action of the manual-keys.

The sub-bass can be secured to the action-board A by angle-clips, as shown, or in other suitable manner.

The operation is as follows: The air being exhausted from the chambers A' and B', as when playing the organ, the keys K being depressed, the button P' presses down the end of the lever L, thereby releasing a stop, L', from the air-inlet opening J. Air being thus admitted to the interior of the pneumatic F, it is, owing to the exhaustion of the air in the surrounding chamber B', caused to immediately expand or swing outward to the position indicated by dotted lines, Fig. 3, pressing back the pin or rod I, and thereby forcing open the valve D, so that the air can enter through the sub-base reed tube, as indicated by arrows, Fig. 3, for sounding the reed R. Then, when the key rises, the lever L being released, again closes the passage J, and equilibrium of air pressure being restored within and without the pneumatic, the valve D is permitted to close by the action of its spring d.

Among the advantages incident to my invention may be mentioned the extreme simplicity of application to use, as the sub-base can be made up quickly and at comparatively small expense, and can be arranged on the organ with little labor, and without interfering with the other parts of the organ, by simply boring through the sound-board and securing the case B in place thereon.

Another advantage is the delicacy and lightness of the touch, since by the arrange-

ment and use of pneumatic mechanism, as herein described, the manual is relieved from the work of opening the valves D, and no extra strain is brought against the keys with which the sub-bass is attached other than that required for simply working the inlet-stops L', which is practically imperceptible in the touch of the keys.

Another advantage is the promptness of response, since the least movement of the key K and inlet-stop L' permits air to pass into the motor F, and the valve D is instantly thrown open to its full extent by the pneumatic action under the effect of the exhaust, and a volume of air is thus put into action through the sub-bass reed-cell before the key-actuated valves are fairly open, which is sufficient to excite vibration in the heavy sub-bass reed and give sound therefrom as soon as the sound from the reeds controlled by the regular key-operated valves commences.

What I claim as of my invention, and desire to secure by Letters Patent, is—

1. A sub-bass for reed-organs, provided internally with an exhaust-chamber, as B', surrounding the tube-board, and within which are arranged valves for closing the several reed-cell passages thereinto, and a corresponding series of pneumatic motors, as F, severally connected for operating the respective valves, with air-inlet passages leading into said pneumatics from the exterior of the casing, and a series of stops or valves closing said inlet-passages, and adapted for connecting with the manual action in a reed-organ, substantially as set forth.

2. The combination, substantially as hereinbefore described, of the casing B, inclosing the air-chamber B', the tube-board C, having cells for containing reeds supported within said chamber, the valve D, the spring d, the tracker-pins I, the pneumatic motors F, having passages leading to the exterior of the case, the inlet-stop valves, the levers L, controlled by the manual-keys, for the purposes set forth.

3. The combination in a sub bass for reed-organs, of the tube-board C, containing reeds R, the valves D, pneumatics F, and tracker-pins I, arranged for operation substantially as set forth.

4. The combination, substantially as hereinbefore described, of the sub-bass section B, provided with reed-cells C and passages J, disposed as shown, the valves D, tracker-pins I, pneumatic fingers F, adjustable levers L, carrying valve-pads L', the fulcrum-support N, pitmen P, having buttons P', and manual-keys K, for the purposes set forth.

Witness my hand this 15th day of May, A. D. 1885.

FRANK STONE.
